UNITED STATES PATENT OFFICE.

GEORGE JOSEPH MURPHY, OF BARADERO, BUENOS AIRES, ARGENTINA.

RAIL-JOINT.

1,365,941.

Specification of Letters Patent. Patented Jan. 18, 1921.

Application filed February 4, 1920. Serial No. 356,282.

To all whom it may concern:

Be it known that I, GEORGE JOSEPH MURPHY, a subject of the King of Great Britain, and a resident of Baradero, F. C. C. A., 5 Buenos Aires, Argentina, have invented a new and Improved Rail-Joint, of which the following is a description.

My invention relates to rail joints and more particularly to a joint involving overlapped rail ends, the general object of the invention being to provide novel joint elements to insure the free expansion and contraction of the rails under changes of temperature, and the maintaining automatically 15 of the joint bolts at right angles to the rails without straining the bolts, as well as the forming of a rail joint mechanically strong to resist both vertical and lateral strain under all load conditions and to prevent 20 jars or shocks as the car passes over the joint.

The stated objects and others as will appear are attained by the novel features hereinafter particularly described and claimed, 25 important features being the provision of an equalizing element at the joint which materially aids in maintaining the joint elements in proper alinement irrespective of the expansion and contraction, a novel form 30 of the overlapping rail ends, and means to insure the free relatively longitudinal movement of the joint elements without undue friction.

Reference is to be had to the accompanying drawings forming a part of this specification, it being understood that the drawings are merely illustrative of practical examples of the invention.

Figure 1 is a plan view of a portion of a 40 railway track embodying my improved joint;

Fig. 2 is a side elevation thereof;

Fig. 3 is a horizontal section;

Fig. 4 is an inner face view of one of the 45 overlapping rail ends;

Fig. 5 is an inner face view of the other overlapping rail end;

Fig. 6 is a transverse vertical section on the line 6—6, Fig. 1;

Fig. 7 is a transverse vertical section on the line 7—7, Fig. 1;

Fig. 8 is a transverse vertical section on the line 8—8, Fig. 4;

Fig. 9 is a transverse vertical section 55 through a modified form of my joint in a

plane corresponding with the line 9—9, Fig. 12;

Fig. 10 is a fragmentary view of the end portion of the equalizing bar, the view showing the inner face of said bar;

Fig. 11 is a cross section on the line 11—11, Fig. 10;

Fig. 12 is a view similar to Fig. 3 but showing a modified form of my invention;

Fig. 13 is a longitudinal vertical section 65 on the line 13—13, Fig. 12;

Fig. 14 is an inner face view of the equalizing bar with anti-friction elements, hereinafter referred to, in position thereon;

Fig. 15 is a perspective view of one of the 70 anti-friction elements employed in the modified form shown in Figs. 12 to 14.

In carrying out my invention in accordance with the illustrated example, the track rails 10 are rabbeted, the rabbet being indicated by the numeral 11, so that the meeting ends of the adjacent rails will present overlapping extensions 12, the base or inner portion of the extension on each rail including a short zone 13, the full height of the 80 rail tread, while the major portion of the extension is of reduced height to lie beneath the head of the adjacent rail. Each extension 12 has the flange 14 thereof widened beyond the remaining portion of the rail 85 flange to strengthen the extension and provide ample base support therefor and the web of the rail has increased thickness as at 15, the increased thickness extending throughout the extension 12 and along the 90 body of the rail a substantial distance adjacent to the extension. The extension 12 has the end 12^a thereof tapered. Those track rails 10 whose extensions 12 overlap at the inside of the track are formed with 95 round transverse bolt holes 16 in the extension 12 thereof and also in the body of the rail adjacent to the extension as clearly shown in Figs. 3 and 4, while those rails 10, the extensions of which overlap at the outside of the track are formed with oval bolt holes 17 in the extension 12 of said rail and in the body adjacent to said extension, the holes 16, 17 registering when the rail ends are overlapped in order to receive transverse 105 bolts 18 having nuts 19. With the rabbeted rail ends overlapped and secured by the bolts 18, the overlapping extensions 12 constitute in effect integral fishplates. The bolts 18 pass also through holes 20^a in an equaliz- 110

ing plate 20 provided in accordance with my invention at the outside of each rail of the track and crossing the joint thereof, said plate being disposed along the webs of the 5 track rails beneath the rail heads between the same and the rail flanges, the holes 23 as seen in Fig. 10 having a notch 23^a at a side thereof to receive the rib 18^a on a bolt 18 adjacent to the bolt head to prevent turning of 10 the bolt. In addition to being engaged by the bolts 18, the equalizing plate 20 is rigidly secured at one end to one track rail and overlaps the adjacent rail and its extension at the outside, said overlapped end being free 15 and unsecured. For securely fastening the one end of the equalizing plate 20, said end is thickened as at 21 and offset laterally inward from the body of said plate so that the thickened end lies snugly against the 20 opposed web of the rail to which it is secured as best seen in Fig. 3. Said thickened end 21 of the equalizing plate is provided at its inner face with a stud 22 received in a corresponding recess 22^a in the web of the 25 adjacent rail 10. Also, said thickened end 21 is formed with a transverse bolt hole 23 registering with a bolt hole 23^a in the track rail, said holes receiving a bolt 24 having a nut 25, said bolt and the stud 22 thus firmly 30 holding the equalizing bar against displacement in any direction relatively to the rail to which it is secured. The bolt 24 is prevented from turning by forming a longitudinal rib 24^a thereon adjacent to the bolt head, 35 the said rib being accommodated in a notch 23^a at a side of the bolt hole 23. Means is provided at the inner face of the equalizing plate between the same and the overlapped outer rail end to reduce the friction when 40 the parts move relatively in response to expansion and contraction of the rails. The anti-friction means in the form of the invention illustrated in Figs. 1 to 7 includes the following: The equalizing plate 20 for 45 its major portion is recessed at the inner face as at 26, thereby presenting upper and lower inwardly directed flanges 26^a and in said recess between said flanges vertical anti-friction rollers 27 are disposed so that the 50 rollers may roll on the inner surface of the equalizing bar and the opposed outer surface of the extension of the adjacent overlapped rail end, that is to say, against the thickened web portion 15. In the form of 55 the invention shown in Fig. 9 and Figs. 12 to 15, the adjacent rail ends 10^a have rabbets 11^a, overlapping extensions 12^b, and zones 13^a corresponding essentially with the features 11, 12 and 13, said extensions having widened base flanges 14^a and said rails 60 10^a having thickened webs 15^b, these features corresponding with the features 14, 15. Bolts 18 are also employed and an equalizing plate 20^c. With a view to present the 65 minimum contact surface between the ex-

pansion plate 20^c and the adjacent overlapped outer rail extension 12^b and thereby reduce the area liable to rust and binding tendency pairs of longitudinally ranging bars are provided, there being a pair of 70 anti-friction bars 20^a on the outer rail 10^a and its extension 12^b and an opposed pair of anti-friction bars 27^b on the equalizing plate 20^c. Said bars have at their ends lateral studs 27^c received in corresponding recesses formed respectively in the outer face of the rail and in the equalizing plate 20^c. Thus, the respective pairs of anti-friction bars are disposed back to back in frictional engagement. Said anti-friction bars are partially let into the opposed faces of the extension 12^b and equalizing plate 20^c by forming shallow longitudinal grooves 12^c, 26^b in said extension and equalizing plate. For securing the equalizing plate 20^c at one end 75 to a rail 10^a, the offset end 21^a of said plate has its stud 22^a formed oval in cross section as best seen in Fig. 13, said stud otherwise corresponding with the stud 22 in being received in a recess 23^b in the rail web. Instead of a bolt 24 as in Figs. 1 to 3, the end 21^a has a stud 24^b integral therewith, the end of said stud being reduced and threaded as at 24^c to receive the nut 25^a, said stud 24^b being oval in cross section. Also, the equalizing plate 20^c in addition to receiving the 80 bolts 18 at that end opposite the end 21^a is provided with an inwardly directed integral stud 28 extending through an oval or equivalent elongated hole in the outer rail 10^a, said stud 28 having a reduced threaded end 28^a passing through a round hole in the extension 12^b of the adjacent overlapping rail. Thus, it will be seen that the expansion plate 20^c is rigidly secured at both ends to the 85 same rail 10^a, that is to say, to the body of said rail and to the extension 12^b thereof. 90

With the described construction the outer overlapping rail ends, by reason of the oval bolt holes therein, are free to move longitudinally relatively to the adjacent inner overlapping rail ends and relatively to the equalizing plate 20 or 20^c, and with the described anti-friction means the joint members are maintained in alinement and under 95 proper pressure with the minimum friction and without straining of the bolts or other parts under the expansion and contraction of the rails. Also, the described structure minimizes the possibility of injury to the 100 rail ends and discomfort to railway passengers by the depression of the near rail end by an approaching train relatively to the far rail end, because of the tapered ends 12^c of the rail extensions 12; this will be clear when 105 considering the fact that with the depression of a rail end by an approaching car wheel, and the rebound of the same under the 110 springiness of the earth and the elasticity of the rail, the opposed rail end is caused 115

also to rebound, the extreme end of the extension of the depressed rail acting by its backlash on the adjacent rail end and therefore the tapering of the rail ends reduces 5 the backlash to a minimum by shortening the arm represented by the rebounding extension.

The making of the anti-friction bars 27^a, 27^b separate from the rails and equalizing 10 plates prevents damage to said anti-friction bars in transit before installation while the form of the anti-friction bars and the provision for their seating facilitates the installation.

15 It should be mentioned that at the junction of the rail head and a zone 13 as well as at the under side of said zone adjacent to the extension, the merging surfaces are curved as at 13^b, 13^c, (see Fig. 4) in order 20 to avoid sharp corners which develop weakness in the rail.

I would state in conclusion that while the illustrated examples constitute practical embodiments of my invention, I do not limit 25 myself strictly to the mechanical details herein illustrated, since manifestly the same can be considerably varied without departure from the spirit of the invention as defined in the appended claims.

30 Having thus described my invention, I claim:

1. In a railway joint, rabbeted rail ends presenting overlapping extensions having bolt holes therein, and transverse bolts passing 35 through said extensions, the one set of bolt holes presenting clearance spaces for the longitudinal movement of the rail end relatively to the bolts; together with an expansion plate secured to one rail end adjacent to the extension thereof and overlapping the other extension.

2. A railway joint having rabbeted rail ends presenting overlapping extensions having bolt holes therein, transverse bolts passing 45 through said extensions, the outer overlapping extension having the bolt holes therein of a size to present clearance spaces for the longitudinal movement of that rail end relatively to the bolts, and an expansion 50 member rigid with one rail end and overlapping the other rail end at the outside thereof.

3. A railway joint having rabbeted rail ends presenting overlapping extensions having bolt holes therein, transverse bolts passing 55 through said extensions, the outer overlapping extension having the bolt holes therein of a size to present clearance spaces for the longitudinal movement of that rail end relatively to the bolts, and an expansion 60 member rigid with one rail end and overlapping the other rail end at the outside thereof; together with anti-friction elements between the opposed faces of said expansion plate and the adjacent overlapped extension.

65 4. In a railway joint, rabbeted rail ends

presenting overlapping extensions having registering bolt holes therein and bolts extending through said holes, those holes in one extension presenting clearance spaces for the longitudinal movement of said extension 70 relatively to the bolts, said extensions for their major portions being of a height to lie beneath the rail heads against the webs of the rails and the outer ends of the extensions being tapered, said extensions having 75 base flanges of a width increased beyond that of the normal flanges of the rails.

5. In a railway joint, rabbeted rail ends presenting overlapping extensions having registering bolt holes therein and bolts 80 adapted to be passed through said holes, said extensions adjacent to the inner ends thereof being of a height to present tread surfaces aligning with the treads of the bodies of the rails, there being curved surfaces at 85 the back of said zones at the top and at the front of said zones at the bottom, the bolt holes of one extension presenting clearance spaces for the longitudinal movement of said extension relatively to the bolts. 90

6. In a railway joint, overlapping rail ends having registering bolt holes, and a separate expansion plate rigidly secured to the one rail end and spaced therefrom to accommodate the other overlapping rail end; together with bolts passing through the overlapping rail ends and through said expansion plate, the bolt holes in that overlapping rail end adjacent to the expansion plate presenting clearance spaces for the free 100 longitudinal movement of said overlapping ends relatively to the other rail ends and relatively to the expansion plate and bolts. 95

7. In a railway joint, overlapping rail ends presenting extensions having registering bolt holes, a separate expansion plate, means to rigidly and detachably secure both ends of said expansion plate to one rail end and spaced therefrom to accommodate the other rail end, and bolts passing through 105 said bolt holes and through said expansion plate, the one overlapping rail end having the bolt holes thereof presenting clearance spaces for the free longitudinal movement of said rail end relatively to the other rail 110 end and to the expansion plate. 115

8. In a railway joint, overlapping rail ends, and a separate expansion plate overlapping the outer rail ends, and bolts passing through said overlapped rail ends and 120 through said expansion plate; together with means to secure the expansion plate rigidly to one rail end, said means including a stud on the expansion plate accommodated in a recess in the rail end to which the expansion plate is secured as well as means adjacent to said stud to clamp the expansion plate in position. 125

9. In a railway joint, overlapping rail ends, an expansion plate rigid with one rail 130

and overlapping the other rail, said expansion plate being recessed in its inner face presenting inwardly directed upper and lower flanges, anti-friction rollers extending 5 into said space of the expansion plate between the flanges thereof to bear against said expansion plate and the opposed overlapped surface of the adjacent overlapped end and bolts passing through said overlapped ends

and said expansion plate, the one rail end 10 being adapted to have longitudinal movement relatively to the other rail end and to the expansion plate under the expansion and contraction of the rails.
